INVENTOR
A. E. Kintner
By W. H. Burridge att.

UNITED STATES PATENT OFFICE.

ALCUIN E. KINTNER, OF PAINESVILLE, OHIO.

MAGNETIC LOCK.

SPECIFICATION forming part of Letters Patent No. 468,807, dated February 16, 1892.

Application filed September 3, 1891. Serial No. 404,628. (No model.)

To all whom it may concern:

Be it known that I, ALCUIN E. KINTNER, a citizen of the United States, residing at Painesville, in the county of Lake and State of Ohio, 5 have invented a certain new and Improved Magnetic Lock, of which the following is a specification.

The nature of my invention relates to a lock having a series of iron or steel tumblers 10 therein, which are attracted by a magnetic key, thereby admitting the easy opening of the lock in the manner hereinafter shown and explained.

That the invention may be fully seen and 15 understood by others, reference will be had to the following specification and drawings, and for the purpose of showing the nature of the said invention one form of a lock is shown and described.

20 Figure 1 is a vertical longitudinal section of a padlock, showing my invention in connection therewith. Fig. 2 is a horizontal cross-section on line $x\bar{x}$, Fig. 1. Fig. 3 is a cross-section on line $x'\bar{x}'$, and Figs. 4 and 5 are cross-sections on lines $x^2\bar{x}^2$ and $x^3\bar{x}^3$, respectively. Fig. 6 illustrates the lock closed. Fig. 7 illustrates the lock open. Figs. 8 and 9 are enlarged views of the magnetic key used in connection with the lock and hereinafter fully explained.

30 In the drawings annexed hereunto one form of a padlock is shown, the following description referring to said lock. I do not, however, confine myself to padlocks alone, as it will be readily seen from the specification that the 35 principal which I claim can be applied to any lock—that is to say, different locks for different purposes, such as mortise-locks, flat interior spring-locks, &c., can be constructed embodying my improvement.

40 In the drawings, A denotes the body of the lock, and B the clasp or bolt, the arms a and a' thereof entering into the two chambers b and b' of the body A. The arms a and a' are notched, as shown at c and c' , Figs. 1, 2, and 45 7. (Best shown in Fig. 7.)

Pivoted to the body of the lock, on the interior thereof, is the cross-arm C. The ends of said cross-arm being held in the notches c and c' of the clasp by the spring d, Fig. 2. A casing D is rigidly fitted in the body of the lock from the lower side, as shown in Figs. 1, 3, 4, and 5, or it may be an integral part of the

body of the lock. The casing D has a portion thereof cut away, as shown in Figs. 1 and 3. Another casing E (preferably cylindrical to 55 avoid confusion of parts in the description) is inserted within the casing D, its interior terminal bearing on the spiral spring e, Fig. 1. This cylinder, as well as casing D, should be constructed of non-magnetic metal.

60 In the construction of the cylinder E lies the important features of the invention. Said cylinder is constructed as follows: A pin f, Figs. 1 and 3, is rigidly attached thereto and extends through the cut-away portion of the 65 casing D. The chamber g is in open connection with the key-hole h. A pin i is rigidly secured across said chamber, near the inner terminal thereof, near the outer terminal of the shell. Beyond the outer extremity of the 70 casing D is arranged a series of steel or iron tumblers k k k, (these tumblers being preferably of cast-iron, as that will not retain the magnetism,) which work loosely in said shell E, the outer terminals of the tumblers k resting on the outer edge of the casing D.

75 I will now describe the practical working of the lock. A key the shank m of which is magnetized and similar in form to the one shown in Figs. 8 and 9 is slotted or sawed, as 80 shown in Figs. 8 and 9 at l. The magnetism of the shank of the key upon said key entering the chamber g will attract the tumblers k, drawing them from their contact with the casing D and permitting the cylinder E to be 85 forced inward against the resiliency of the spring e, forcing the pin f alongside of the cross-bar C. The slot l of the key will engage the pin i and by a partial revolution of the key, the pin f being in contact with the side 90 of the cross-arm C, will release said cross-arm from the notches c and c', when, owing to the resiliency of the spiral spring n, Fig. 1, the arm a' of the clasp or bolt B will be raised out of the chamber b' and the lock is open, 95 as shown in Fig. 7. In closing the lock it is simply necessary to force the clasp into the chambers b and b' , and when the cross-arm C registers with the notches c and c' the resiliency of the spring d, Fig. 2, will force the 100 said cross-arm into the notches and retain it therein until released by means of the key.

The key shown in Figs. 8 and 9 is provided with a covering o and when not in use is

inclosed therein, as shown in Fig. 8. This is not, however, necessary, the magnetism of the key being the most essential feature thereof. The casing of said key is simply for convenience in carrying said key in the pocket with other keys or magnetic articles.

Having described my invention, what I claim, and desire to secure by Letters Patent, is—

- 10 1. In a magnetic lock, the combination of a series of tumblers arranged loosely within a cylinder, said cylinder within a casing D, having an opening therein, and a pivotal cross-arm C, operating conjointly with a pin f, attached to the cylinder and in contact with the cross-arm C, actuated by a grooved magnetic key, substantially in the manner as and for the purpose set forth.
- 15 2. In a magnetic lock, a cross-arm pivoted within a cylinder, the terminals of said cross-

arm susceptible of engagement and disengagement with the notches c and c', in combination with the pin f, tumblers k k k, and casing D, in conjoint operation with a slotted magnetic key and engaging pin i, arranged 25 in the manner as and substantially for the purpose set forth.

3. In a magnetic lock, a series of non-magnetized tumblers arranged within a cylinder around the key-opening, in combination with the pin f, cross-arm C, engaging pin i, and the slotted magnetic key whereby the bolt is readily disengaged and the lock opened, substantially in the manner set forth.

In testimony whereof I affix my signature in 35 presence of two witnesses.

ALCUIN E. KINTNER.
